ORNAMENTAL BASE FOR CHRISTMAS TREES

William M. Flanagan, Philadelphia, Pa.

No Drawing. Application February 17, 1937,
Serial No. 126,307

2 Claims. (Cl. 41—10)

The present invention pertains to the art of ornamentation and more particularly to the art of ornamental fabric bases adapted to be used in connection with Christmas trees and to simulate the natural surroundings of the tree. The primary object of the invention has been to produce a Christmas tree ornamental base which is artificially colored to simulate snow, grass, moss, or other natural surroundings of the tree.

10 The invention can best be understood from a description of the method of manufacturing it. In the production of the ornamental base of the invention a fibrous material which may be jute, hair, wool waste, or other natural fiber, is first 15 carded or garnetted in a conventional manner. The carded fibrous material is then made into a bat by conventional means, such as passing it through a Blamire feed machine. The coherent fibrous mass produced in this manner should 20 be of thinner consistency, i. e., less fibers per square inch, than the consistency of similar fibrous materials which are ordinarily produced in carding and batting such fibers to produce fabrics such as rugs, for example.

25 After the carding and batting operations are completed, the bat is needled to a suitable backing, which may be burlap, tobacco cloth, paper, or other suitable inexpensive backing surface. Care is taken in the performance of this needling operation to effect it in such a way as to cause 30 the individual fibers to stand away from the backing surface instead of being pressed down into a substantially horizontal position against this surface. This can be accomplished either 35 by reducing the number of needles employed in this operation below that employed in producing conventional fabrics by needling of batted fibrous material to backing surfaces, or by speeding up the rate of feed of the backing material and bat through the needle loom. The fabric material which leaves the needle loom may be cut to desired sizes and bound with thread, or it may 40 be left unbound and sold in strip form.

This material is left unsized, since sizing would 45 cause the individual fibers to be compressed against the backing surface and would therefore result in the production of a fabric material more

or less analogous to an ordinary rug, and this material would not achieve the desired effect of simulating snow, grass, moss, or other material naturally surrounding an evergreen tree.

In the step of processing the strip produced in the above-described manner to effect the desired color simulation, it may be bleached to 5 simulate snow, dyed to simulate grass or moss, or printed to form an ornamental design. It may, for example, be printed in two or more 10 colors in order to simulate a lawn provided with dirt paths, or any other desired design.

Alternatively, the individual fibers which are 15 processed to produce the ornamental base of the invention may be bleached or dyed prior to the performance of the steps of carding and batting, or at an intermediate stage in the process of manufacture.

I am aware that the general sequence of process steps described above is known in the art of 20 manufacturing rugs and other fabric articles, and no claim to invention is made in the performance of the succession of steps described. The use of the fabric in an unsized condition, the needling 25 of the bat to the backing material in such a manner as to cause the individual fibers to stand away from the backing material, and the thinness of the bat do, however, produce a highly ornamental effect which simulates the natural 30 surroundings of a Christmas tree in a manner which could not be achieved by more conventional fabrics.

I claim:

1. An ornamental Christmas tree base comprising a thin unsized bat of fibrous material 35 needled at widely spaced points to a backing material, the strands of said fibrous material being so arranged as to stand away from the backing material, and the whole being suitably colored.

2. An ornamental Christmas tree base comprising a thin unsized bat of fibrous material 40 needled at widely spaced points to a backing material, the strands of said fibrous material being so arranged as to stand away from the backing material, and the fibers thereof being suitably 45 multi-colored.

WILLIAM M. FLANAGAN.
